FIG. 1

FIG. 2

FIG. 4

FIG. 3

FIG. 5

FIG. 6

FIGURE 1 is a side elevational view of an electric plug showing my new design, the fragmentary, broken-line showing of wires being for illustrative purposes only;

FIGURE 2 is a bottom plan view thereof;

FIGURE 3 is an elevational view of the side opposite that seen in FIGURE 1, partially in section;

FIGURE 4 is a left-end elevational view thereof;

FIGURE 5 is a right-end elevational view thereof; and

FIGURE 6 is a top plan view of the plug as seen in FIGURE 1.

I claim:

The ornamental design for an electric plug, substantially as shown and described.
